To all whom it may concern:

Be it known that Julius C. Barnes, a citizen
of the United States, residing at Columbus, in the
county of Muscogee and State of Georgia, has in-
vented a new, original, and ornamental Design
for a Laundry Heater, of which the following is a
specification, reference being had to the accom-
panying drawing, forming part thereof, wherein—

Figure 1 is a top plan view of a laundry heater
showing my new design;

Figure 2 is a side elevational view thereof; and
Figure 3 is a front elevational view thereof.

I claim:

The ornamental design for a laundry heater,
as shown.

JULIUS C. BARNES.
